Specification for Design.

Patented Apr. 26, 1921.

Application filed September 30, 1920. Serial No. 413,929. Term of patent 14 years.

To all whom it may concern:

Be it known that I, JOSEPH O. BALDA, a citizen of Hungary, and resident of Newark, county of Licking, and State of Ohio, have invented a new, original, and ornamental Design for a Glass Goblet or other Similar Article of Manufacture, of which the following is a specification, reference being had to the accompanying drawings, in which—

The figure is a side elevation of a glass goblet, showing my new design.

I claim:

The ornamental design for a glass goblet or other similar article of manufacture, as shown.

In testimony whereof I have hereunto affixed my signature in the presence of two subscribing witnesses.

JOSEPH O. BALDA.
